[57] CLAIM

The ornamental design for a workstation cluster, as shown and described.

DESCRIPTION

FIG. 1 is a perspective view of a workstation cluster showing my design;

FIG. 2 is a top plan view thereof;

FIG. 3 is a front elevational view thereof; and

FIG. 4 is a right side elevational view, the left side being identical thereto;

FIG. 5 is a perspective view of a modified form of the workstation cluster;

FIG. 6 is a top plan view of the modified form of the workstation cluster show in FIG. 5;

FIG. 7 is a front elevational view thereof; and

FIG. 8 is a right side elevational view, the left side being identical thereto.

FIG. 1

FIG. 2

FIG. 3

FIG. 4

FIG. 5

FIG. 6

FIG. 7

FIG. 8

UNITED STATES PATENT AND TRADEMARK OFFICE
CERTIFICATE OF CORRECTION

PATENT NO. : D 332 189
DATED : January 5, 1993
INVENTOR(S) : Mary Brodbeck

It is certified that error appears in the above-identified patent and that said Letters Patent is hereby corrected as shown below:

On the title page of the patent, Column 1,
in Item [*] Notice:, line 2; change "Dec. 15, 2009"
to ---Dec. 15, 2006---.

Signed and Sealed this
Fourth Day of January, 1994

Attest:

BRUCE LEHMAN

Attesting Officer

Commissioner of Patents and Trademarks
